UNITED STATES PATENT OFFICE.

JACOB KRUMSCHEID, OF BOSTON, MASSACHUSETTS.

DOOR-CHECK.

SPECIFICATION forming part of Letters Patent No. 317,147, dated May 5, 1885.

Application filed December 1, 1884. (Model.)

To all whom it may concern:

Be it known that I, JACOB KRUMSCHEID, of Boston, in the county of Suffolk, of the Commonwealth of Massachusetts, have invented a new and useful Improvement in Door-Checks; and I do hereby declare the same to be described in the following specification, and represented in the accompanying drawings, of which—

10 Figure 1 is a front view, Fig. 2 a rear view, and Fig. 3 a horizontal section, of my said invention, the nature of which is defined in the claims hereinafter presented, Figs. 1 and 3 showing the door-check as applied to a door-casing and the door thereof.

15 In the said drawings, A denotes the door-casing, to which is secured the door-check by means of screws screwed through ears *a a* on the standard or frame B of the said door-check and into the casing.

Pivoted to one end of the standard B, as shown at *b*, is an arm, C, which extends in front of and in the same horizontal plane with the said standard, and has attached to its other 25 end a bell-shaped case, E. The arm C is curved at *d*, and in such curved part has a slot, *e*, in which is to travel a roller, *f*, that revolves on a stud, *f'*, attached to a lever, D, fulcrumed to the standard B at *g*. To the 30 shorter arm of the said lever is pivoted a rod, *g'*, which serves as a support for one end of a spiral spring, *s'*, that encompasses the said rod and abuts against the shoulder *u* on the said rod. The other end of the spring in like 35 manner is supported by a short rod, *i'*, fastened by a screw-nut to a shoulder or projection, *h*, against which the spring abuts, projecting from the standard B, all as represented. The longer arm of the said lever D is bent down- 40 ward at *i*, and thence past the bell-shaped case E, and has in its end a long slot, *k*, in which is to freely travel a roller, *l*, that revolves on a stud, *m*, projecting upward from a bracket, F, which is attached by means of 45 screws to a door, as shown at *n*.

To the end of the standard B, directly in rear of the bell-shaped case, is fastened a block, G, of wood or other material, in shape corresponding to that of the interior of the case, by

means of two screw-eyes connected to each other, and one screwed through the said standard and the other into the said block, as represented at *o*. The bell-shaped case has a flat rim, as exhibited at *p*, between which and a flat ring corresponding in shape and size to 55 the said rim is secured a bellows or leather diaphragm, *q*, by means of screws *r r r*, &c. The said bellows or diaphragm extends loosely across and covers the rear or open end of the case, and is attached at its middle to the 60 block G.

In the case E, as shown at *s*, is a short cylindrical tube in the end of which is a valve, *t*, made so as to readily admit air into the case, and also allow it to slowly escape therefrom. 65

From the above it will be seen that when the door is opened the lever D will be pushed outward by means of the stud *m* and roller *l*, traveling in the slot *k*. The said lever in moving outward will cause the arm C to move in 70 the same direction, by means of the stud *f'* and roller *f*, traveling in the curved slot *e*, and thus cause the case E to move away from the block G, and by so doing expand the bellows *q*, the air to fill such bellows passing inward through the valve *t*, the spiral spring *s'* being in the meantime contracted by the shorter arm of the said lever D. On the door being released, the spiral spring, acting 75 reversely on the lever D, will have a tendency 80 to rapidly close the door, but the said case in going backward will, with the block G, cause the diaphragm *q* to act as an air-cushion, from which the air slowly escapes through the seat of the valve *t*, thus allowing the door to 85 gradually close without slamming.

I claim—

1. The door-check, substantially as described, consisting of the frame or standard B, the slotted arm C, carrying the case E, having 90 the valve *t*, the block G, connected to the said standard, the diaphragm or bellows *q*, attached to the said case and block, the lever D, fulcrumed to the said standard and having the stud *f'* and roller *f*, the longer arm of the 95 said lever slotted to receive the stud *m*, and roller *l*, projecting upward from the bracket F, and its shorter arm connected to the rod *g'*,

which with the rod *i*, attached to the shoulder *h*, supports the spiral spring *s*, all being essentially as represented.

2. The combination, with the door-casing and door thereof, of the door-check, substantially as described, consisting of the frame or standard *B*, slotted arm *C*, case *E*, valve *t*, block *G*, bellows *q*, slotted lever *D*, stud *f*,

roller *f*, rods *g*' and *g*', shoulder *h*, spiral spring *s*', bracket *F*, stud *m*, and roller *l*, all being so arranged and to operate essentially in manner as set forth.

JACOB KRUMSCHEID.
